UNITED STATES PATENT OFFICE.

CLIFTON K. BAUMANN, OF NEW YORK, N. Y.

FABRIC-BOLT BOARD.

1,218,358.

Specification of Letters Patent.

Patented Mar. 6, 1917.

Application filed April 15, 1915, Serial No. 21,537. Renewed January 24, 1917. Serial No. 144,310.

To all whom it may concern:

Be it known that I, CLIFTON K. BAUMANN, a citizen of the United States, and a resident of the city of New York, borough 5 of Manhattan, in the county and State of New York, have invented a new and Improved Fabric-Bolt Board, of which the following is a full, clear, and exact description.

10 Among the principal objects which the present invention has in view are: to provide a board of the character mentioned having relatively rigid permanent side edges and relatively fragile removable sides for preventing the collapsing of fabric wound on said board; and to reduce the cost of construction and lighten the weight of said board.

Drawings.

20 Figure 1 is a perspective view of a board constructed and arranged in accordance with the present invention;

Fig. 2 is a cross section of the same taken 25 on the line 2—2 in Fig. 1;

Fig. 3 is a cross section taken on the line 3—3 in Fig. 1;

Fig. 4 is an end view of a board, the opening to the sample box being closed;

30 Fig. 5 is a longitudinal section taken as on the line 5—5 in Fig. 4.

Description.

As seen in the drawings, the board is provided at each end with a box 10. Each box 35 has sides 11. The sides 11 are each stamped to form a raised portion and a rabbet recess 12 adjacent the side edges and the rear edge of each box. The boxes are faced with a strip having rounded form ends 13 and 40 elongated openings. The openings 19 referred to are each surrounded on three sides by channels 14, said channels being exposed at one end of said openings to receive closure strips 20. The closure strips are imprinted as desired.

The boxes 10 are preferably divided by a partition 15 to form two compartments. It will be understood that this construction 50 may be varied by using any suitable number of partitions to divide the box into a desired number of compartments.

The rabbet recesses 12 at the side edges of the boxes 10 are provided to receive the 55 folded end edges of half round rails 16.

The rails 16 are formed to the full length of the board constructed in accordance with the present invention, and shaped to the ends 13 of the facing strips of the boxes 10.

Intermediate the sections where the rails 16 rest upon the recesses 12 of the boxes 10, said rails are provided with rabbeted edges 17, which correspond with the recesses 12. The rabbeted edges 17 coöperate with the recesses 12 to form a pocket to receive panels 18.

It is preferred that the boxes 10 and the rails 16 should be constructed from metal, and that the panels 18 should be constructed from cardboard. The object of the composite construction is two-fold, to wit, to lighten the completed board, and to reduce the cost thereof. By the arrangement shown and described, it is obvious that the rails 16 may be constructed from a relatively 70 cheap grade of material, and the boxes 10, being made from relatively small sheets, may be completed at a corresponding diminution in price.

The panels 18 may be held in the rabbeted edges 17 and recesses 12 by any suitable means, that employed by me being to attach the boards to the recesses and edges with any suitable adhesive. The panels 18 may be utilized for imparting directions or information desired by the trade in which the board is employed. Also, it is obvious that the panels 18 may be from time to time renewed.

Claims.

1. A fabric bolt board, comprising a plurality of boxes; and a plurality of rails fixedly attached to said boxes for forming the edges of the completed board.

2. A fabric bolt board, comprising a plurality of boxes; a plurality of rails fixedly attached to said boxes for forming the edges of the completed board; and removable means for closing the ends of said boxes.

3. A fabric bolt board, comprising a plurality of boxes; a plurality of rails fixedly attached to said boxes for forming the edges of the completed board; and a plurality of side panels uniting in service said boxes 105 and said rails.

4. A fabric bolt board, comprising a plurality of boxes; a plurality of rails fixedly attached to said boxes for forming the edges of the completed board; and a plurality of 110

2
covering panels fixedly attached in service to form a flush surface with said boxes and said rails.

5. A fabric bolt board, comprising a plurality of boxes; a plurality of rails fixedly attached to said boxes for forming the edges of the completed board; a plurality of covering panels fixedly attached in service to form a flush surface with said boxes and 10 said rails; a plurality of name cards covering the end openings of said boxes; and means for removably holding said cards in service.

6. A fabric bolt board, comprising a plurality of boxes; a plurality of rails fixedly attached to said boxes for forming the edges 15

of the completed board; a plurality of covering panels fixedly attached in service to form a flush surface with said boxes and said rails; a plurality of name cards covering the end openings of said boxes; means for removably holding said cards in service, said means embodying channel members surrounding the openings of said boxes.

In testimony whereof I have signed my 25 name to this specification in the presence of two subscribing witnesses.

CLIFTON K. BAUMANN.
